(57) **CLAIM**

The ornamental design for a display screen with graphical user interface, as shown and described.

DESCRIPTION

FIG. 1 is a front view of a display screen with graphical user interface showing our new design; and, FIG. 2 is a front view thereof in accordance to an alternate embodiment.

The outermost broken line perimeter showing of the display screen and all other broken line showing elements of the graphical user interface do not form part of the claimed design.
